UNITED STATES PATENT OFFICE.

SIDNEY H. SHORT, OF CLEVELAND, OHIO.

MOTOR-MOUNTING FOR ELECTRIC CARS.

SPECIFICATION forming part of Letters Patent No. 611,461, dated September 27, 1898.

Application filed June 26, 1897. Renewed May 19, 1898. Serial No. 681,175. (No model.)

To all whom it may concern:

Be it known that I, SIDNEY H. SHORT, a citizen of the United States, residing at Cleveland, in the county of Cuyahoga and State of Ohio, have invented a new and useful Motor-Mounting for Electric Cars, of which the following is a specification.

This invention relates to motor-mountings for electric cars.

- 10 The object of the invention is to provide a motor-mounting for electric cars of simple construction wherein the motor-armature and the truck-axle are brought into closer relation, whereby the same degree of speed reduction between the shaft and axle as heretofore may be secured with smaller-sized reduction-gears, thereby economizing space and permitting the employment of larger sizes of motors.
- 20 The invention consists, substantially, in the construction, combination, location, and relative arrangement, all as will be more fully hereinafter set forth, as shown in the accompanying drawings, and finally specifically 25 pointed out in the appended claims.

Referring to the accompanying drawings and to the various views and reference signs appearing thereon, Figure 1 is a view in end elevation of a motor in its operative relation to a car-axle in accordance with my invention, the motor-shaft and the car-axle being in transverse section. Fig. 2 is a plan view of the same. Fig. 3 is a view in front elevation of the same. Fig. 4 is a view similar to Fig. 35 1, indicating in dotted lines the principle of the present improvement over the prior art.

The same part is designated by the same reference sign wherever it occurs throughout the several views.

- 40 In the equipment of modern electric cars it is a matter of material importance to provide motors of as large a capacity as possible, so that the motor may be enabled to develop sufficient power to meet all the exigencies of a varying traffic. It is also necessary to employ suitable reduction-gears between the motor-shaft and the driven axle. In the prior art any increase in the size of the motor necessarily resulted in an increase in the diameters of the reduction-gearing in order for the gear on the axle to reach and to intermesh with the gear on the motor-shaft, and since

the gear on the axle cannot exceed in diameter the size of the car-wheel it will be readily seen that the size of the motor, and hence the 55 capacity thereof, is necessarily prescribed. To obviate this difficulty and to bring the axle into closer proximity to the motor-shaft is the purpose of the present invention.

Referring to the accompanying drawings, 60 reference sign A designates the motor-shaft; B, the axle; C, the motor-armature; D, the car-wheel; E, the field-magnets; F, means for supporting the field-magnets frame from the car-body or truck-frame; G H, the reduction-gears, respectively mounted on the motor-shaft and the car or truck axle. The motor employed is of the multipolar type, employing four or more wound magnetic poles supported radially within the field-magnet-supporting ring or frame, and in carrying out the purpose of my invention and in order to secure the desirable ends had in view I so relatively arrange the field-magnet frame that the car or truck axle B passes within the magnetic 75 ring of the motor-field. This idea may be carried into practical effect in several ways. For instance and as shown in Fig. 1, the field-magnet frame may be constructed in two halves or parts K L, suitably secured together 80 and sleeved or otherwise mounted upon the axle B or having seats adapted to receive said axle, said journal-bearing being formed within the periphery of the field-magnet frame. In Fig. 4 is shown a slightly-different arrangement embodying the same principle and wherein the field-magnet-supporting ring M is provided with an inwardly-projecting casting N, which forms a journal-bearing for the car or truck axle.

90 From the foregoing description it will be seen that I provide a construction and arrangement wherein is employed a multipolar motor wherein the poles project radially within the supporting-ring thereof and receive 95 therein the field windings or coils, the motor-armature being arranged to revolve in the space surrounded by said multiple polar projections, and hence the lateral distance between the motor-shaft and the car or truck 100 axle is very much shortened, thus permitting the size of the motor, and hence its capacity, to be increased without increasing the size of the reduction-gears. Moreover, by the construc-

tion described I am enabled to tilt the motor to a point above the axle, as indicated in Figs. 1 and 3. This is a material feature, for any increase in the size of the motor when the 5 motor-shaft and the car-truck axle are in the same horizontal plane causes the outer periphery of the motor to approach objectionably near the surface of the road-bed; but by the present construction I am enabled to tilt the 10 motor and without increasing the diameter of the reduction-gears, thereby providing a desirable clearance between the road-bed and the motor even with a motor of increased size.

The advantages of the construction above 15 described are particularly apparent in elevated-railway work, wherein it is customary to provide a guard-rail in the road-bed, as indicated at P, Fig. 3, adjacent to and parallel with the track-rails. These guard-rails are 20 located in the vertical plane of the reduction-gears G H, and therefore still further prescribe and limit the diameters of said gears. Again, in elevated-railway equipments the 25 importance of employing as large motors as possible is increased by reason of the fact that in the economical operation of such roads it is desirable, during certain hours of the day, to employ several cars as trailers, and hence at those hours the motors on the motor-car are 30 called upon to develop a much larger power than at other hours of the day, when the traffic falls off, and when it is not economical or desirable to run the maximum number of cars 35 in the train. By the foregoing construction I am enabled to provide a larger-sized motor than would be possible otherwise.

Having now set forth the object and nature of my invention and the manner of carrying the same into practical effect, what I claim as

new and useful and of my own invention, and 40 desire to secure by Letters Patent of the United States, is—

1. In a motor-mounting for electric cars, the combination with a multipolar motor and an axle, and gearing connecting the same, said 45 axle arranged to pass within the magnetic ring of the motor-field, as and for the purpose set forth.

2. The combination with a motor armature and shaft, a supporting-frame for multiple 50 magnetic poles of the motor-field, said frame having bearings formed within the magnetic ring of such field, an axle arranged to be received in said bearings, and intermeshing gears mounted respectively on said shaft and 55 axle, as and for the purpose set forth.

3. The combination with a motor armature and shaft, a sectional supporting-frame for the motor-field, bearings formed in the sections of 60 said frame within the periphery thereof, an axle arranged to be received in said bearings and gearing connecting said shaft and axle, as and for the purpose set forth.

4. In a motor-mounting for electric cars, the combination of a multipolar motor and an 65 axle, arranged to pass within the magnetic ring of the field of such motor the shaft of said motor being arranged in a higher plane than said axle, and intermeshing gears respectively mounted on said motor shaft and 70 axle, as and for the purpose set forth.

In witness whereof I have hereunto set my hand, this 23d day of June, 1897, in the presence of the subscribing witnesses.

SIDNEY H. SHORT.
